UNITED STATES PATENT OFFICE.

JOHN WENNEN AND CHARLES HART, OF FRISCO, UTAH, ASSIGNORS OF
ONE-THIRD TO JOHN H. JOHNS, OF SAME PLACE.

ORE-CONCENTRATOR.

SPECIFICATION forming part of Letters Patent No. 558,915, dated April 21, 1896.

Application filed September 19, 1895. Serial No. 563,003. (No model.)

To all whom it may concern:

Be it known that we, JOHN WENNEN and CHARLES HART, citizens of the United States, residing at Frisco, in the county of Beaver 5 and Territory of Utah, have invented certain new and useful Improvements in Ore-Concentrators; and we do hereby declare the following to be a full, clear, and exact description of the invention, such as will enable others skilled in the art to which it appertains to make and use the same.

This invention relates to certain new and useful improvements in ore-concentrators; and it has for its objects, among others, to provide a simple and cheap device of this class for concentrating gold, silver, copper, lead, and other valuable ores by water, so as to bring the minerals from ten tons of ore to one ton of concentrates, or if the ore contains, say, a large quantity of copper or lead or any low-price metal it can be reduced from four to six to one, or if it only contains, say, a few ounces of gold or silver to the ton fifteen or twenty tons can be reduced to one, and so on. 25 The concentrator is of novel construction, whereby more satisfactory results are attained, and simple means are provided for rotating it.

Other objects and advantages of the invention will hereinafter appear, and the novel features thereof will be specially defined by the appended claims.

The invention in this instance resides in the peculiarities of construction and the novel 35 combination and arrangements of parts, all as more fully hereinafter described, shown in the drawings, and then particularly pointed out in the claims.

The invention is clearly illustrated in the 40 accompanying drawings, which, with the letters and figures of reference marked thereon, form a part of this specification, and in which—

Figure 1 is a top plan view of our improved 45 concentrator with portions removed. Fig. 2 is a vertical section through the same on the line $x-x$ of Fig. 1. Fig. 3 is a detail showing the openings in the center of the heads.

Like letters and figures of reference indicate like parts in all the views.

Referring now to the details of the draw-

ings by letters and figures, A designates the supporting-framework, which may be of any desired material and of the required height.

B is the central shaft, which is mounted to 55 revolve in suitable bearings, being loosely stepped at its lower end in a socket B', as seen in Fig. 2. Motion is imparted to this shaft in the following manner.

C is a horizontal shaft mounted in suitable 60 bearings on the framework and carrying near its inner end a worm C', which meshes with a worm-wheel B² on the upper end of the shaft B, as shown, while upon the outer end of the shaft C is a bevel-pinion C², which meshes with 65 the bevel-pinion D' on the vertical shaft D, mounted in suitable bearings and provided with a crank d, designed to be connected with any suitable source of power. (Not shown.) This constitutes a simple means for operating 70 the concentrator and permits of the machine being set up in any desired position.

E is a cast-iron center fast on the shaft B and having provision for the reception and securing of the radial arms E', which may be 75 secured thereto in any suitable manner and which extend to and are secured to and supported upon the outer ring E², said arms being arranged at an inclination, as shown in Fig. 2.

E³ are supports or a ring secured to the radial arms between their ends, as shown, and secured to the same is the plank or platform F, which constitutes a smooth table extending from the point x to the point x', with a 80 grade or incline toward the center. 85

G is the launder, and G' the heads for bringing the water from said launder to the concentrator. The water that brings in the ore after it is crushed enters the launder at the point 1 and feeds the heads from the said point 90 1 to the point 2 through holes g' in the center of the heads, which incline in opposite directions toward said holes, as seen best in Fig. 2, and the water is distributed by the buttons G², and from these openings it goes onto the concentrator at the points x very slowly, so that the dirt will settle on the table or platform 95 F and the water and the light dirt pass off therefrom into the launder H, which is arranged at this point concentric with the inner 100 periphery of the said table, as shown. Then clear water is brought into the launder G at

the points 3, and flows from these points to the points 4 and 5 and is distributed over the heads G' from the point 4 to the point 5 the same as the pulp. This is for cleansing the 5 ore that has settled on the table from the pulp, washing the waste off into the launder H, as will be readily understood.

I is a water-supply pipe for supplying water, by which the concentrates are washed into the 10 launder H from x to x' and from this launder taken away to a tank or other receptacle and allowed to settle. The waste water is conducted away from the launder H by the trough or pipe J and the second-class matter by the 15 pipe or conduit K. This latter material may be saved and worked again, if desired.

In order to assist the concentrates in being moved from the platform into the launder H, we employ a reciprocatory brush L, arranged 20 to be moved over the said platform and actuated by connection with the crank of the shaft or rod D.

Modifications in detail may be resorted to without departing from the spirit of the invention or sacrificing any of its advantages. 25 For instance, the power may be applied directly to the shaft C and motion given to the vertical shaft D through the medium of the bevel-pinions on the said shafts C and D. In 30 fact, this latter way will be found preferable. When power is applied directly to the vertical shaft or rod D, it should be provided with a separate crank for the attachment of the rod that actuates the reciprocatory brush.

35 Upon reference to Fig. 2 the manner of connection and operation of the brush L will be more clearly understood. In this view the brush is shown as carried by the lower end of the arm L', which is pivotally mounted at 40 its upper end, as at l, while between its ends it is connected by rod or bar L² with the crank d of the vertical shaft or rod D. The connection between the lower end of the rod L' and the brush may be of any suitable form of pivotal connection whereby the necessary movements may be given to the brush.

By the construction hereinbefore shown and described we provide a device by which more satisfactory results are attained, the 50 proportion of ore saved being greater and the consequent waste less than by prior construc-

tions. The reciprocatory device for assisting the ore in its movement down the platform is important, while the brush connected with the vertical rod serves an important function 55 and by the peculiar arrangement thereof and its actuating means requires but minimum power for its actuation.

What is claimed as new is—

1. The combination with the rotatable platform and the heads, of a reciprocatory brush mounted to move over said platform to and from the center radially, and carried by a rod pivotally mounted at its upper end for assisting the ore in its movement down said platform, as set forth.

2. The combination with the main vertical shaft and the platform carried thereby, of the worm - wheel on said shaft, the horizontal shaft, the worm thereon meshing with said 70 worm-wheel, the bevel-pinion on said horizontal shaft, and the vertical shaft having a crank and a bevel-pinion meshing with the bevel-pinion on the horizontal shaft, and a reciprocatory brush arranged to be moved over 75 the platform radially to and from the center to assist the ore to the discharge at the center and operatively connected with said vertical shaft substantially as and for the purpose specified.

3. The combination with the vertical shaft and the inclined platform carried thereby, of the launder arranged concentric with the inner periphery of the platform, a water-pipe for washing the concentrates into said launder a worm-wheel on said shaft, a horizontal shaft carrying a worm meshing with said worm-wheel, a bevel-pinion on the horizontal shaft, a vertical rod having a crank and carrying a bevel-pinion, a reciprocatory brush 90 arranged over said platform to be moved radially with relation to said platform and means connecting the same with said rod, substantially as and for the purpose specified.

In testimony whereof we have signed this 95 specification in the presence of two subscribing witnesses.

JOHN WENNEN.
CHARLES HART.
